UNITED STATES PATENT OFFICE

149,274

DESIGN FOR A SANDGLASS

Marianne L. Lavine, Bala-Cynwyd, Pa.

Application December 4, 1946, Serial No. 135,246

Term of patent 3½ years

(Cl. D42—7)

To all whom it may concern:

Be it known that I, Marianne L. Lavine, a citizen of the United States, residing at Bala-Cynwyd, Pennsylvania, have invented a new, original, and ornamental Design for a Sandglass, of which the following is a specification, reference being had to the accompanying drawing, constituting a part thereof.

Fig. 1 is a front elevational view of a sandglass, showing my new design; and

Fig. 2 is a side elevational view of the same.

I claim:

The ornamental design for a sandglass, substantially as shown.

MARIANNE L. LAVINE.
